UNITED STATES PATENT OFFICE

JOSEPH H. OKUN, OF BROOKLYN, NEW YORK, ASSIGNOR TO KNY-SCHEERER CORPORATION, OF NEW YORK, N. Y., A CORPORATION OF NEW YORK

DESIGN FOR A BEDPAN WASHER

Application filed October 7, 1929. Serial No. 32,963. Term of patent 14 years.

To all whom it may concern:

Be it known that I, JOSEPH H. OKUN, a citizen of the United States, residing at 1854 Ocean Avenue, Brooklyn, in the county of Kings and State of New York, have invented a new, original, and ornamental Design for a Bedpan Washer, of which the following is a specification, reference being had to the accompanying drawing, forming part hereof.

I claim:

The ornamental design for a bedpan washer as shown.

JOSEPH H. OKUN.
